UNITED STATES PATENT OFFICE

2,124,190

SWITCH STAND

Samuel L. Eastburn, Sloatsburg, N. Y., assignor, by mesne assignments, to The American Brake Shoe and Foundry Company, New York, N. Y., a corporation of Delaware

Application May 27, 1937, Serial No. 145,000

1 Claim. (Cl. 246—412)

The invention relates to railway track equipment and, more particularly, to switch stands for operating railway switches.

The invention is shown applied to a switch stand of the general type disclosed in Patent No. 1,443,955, granted February 6, 1923 to William C. Kidd, although it will be apparent that the invention may be applied to other types. This stand is of the automatic type and comprises essentially a casing in which is journalled a star block yieldably held in position by spring pressed rollers. A vertical spindle passes through the star block and has connection with the switch. An arm is pivoted to the spindle and engages in grooves in the star block. A hand lever operable in a vertical plane is pivoted to the base of the switch stand and has a cam surface for engaging the operating arm. Throwing the hand lever from one position to the other, lifts the operating arm out of its groove, moves it in a horizontal plane to throw the switch, dropping it in the next groove.

While switch stands of this general construction have been eminently satisfactory and dependable, some trouble has been experienced by foreign matter getting into the grooves on the star block. Sand, snow and ice collects in these slots, and sometimes the padlock chain for locking the switch stand, interfering with and delaying the operation of the stand.

According to the invention, protecting devices are provided in the form of a circular disc or plate attached to the operating arm, this disc having depending side walls and forming a protective casing which overlies the slots in the star block and protects them from foreign matter, thereby insuring unhindered engagement between the operating arm and the said slots, and increasing the safety of the switch stand and speeding up its operation.

The invention also consists in certain new and original features of construction and combination of parts hereinafter set forth and claimed.

Although the novel features which are believed to be characteristic of this invention will be particularly pointed out in the claim appended hereto, the invention itself, as to its objects and advantages, and the manner in which it may be carried out, may be better understood by referring to the following description taken in connection with the accompanying drawings forming a part thereof, in which—

Fig. 1 is a plan view of the improved switch stand;

Fig. 2 is a section on the line 2—2 of Fig. 1;

Fig. 3 is a horizontal section on the line 3—3 of Fig. 5;

Fig. 4 is a section on the line 4—4 of Fig. 1; and

Fig. 5 is a vertical side elevation of the switch stand looking toward the switch.

In the following description and in the claim, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, the switch stand comprises a casing indicated, in general, by 10 having base flanges 11 for spiking or otherwise securing to the railroad ties. The casing has upstanding sides and is covered by a three-part covering comprising a mid-section 12 and easily removable end sections 13 and 14. This type of cover is described in detail and claimed in my Patent No. 1,783,283, granted December 2, 1930.

Seated within the casing 10 and journalled in the mid-cover section 12 is a star block 15 having four recesses engageable by the spring pressed rollers 16, as indicated in Fig. 3 and described more in detail in the aforementioned Kidd patent. The top of star block 15 is provided with four slots 30 opening upwardly. Journalled within the star block 15 is a vertical spindle 17 passing through the bottom of the casing 10 and having an arm 19 for connection to a connecting rod (not shown) extending to the switch. The upper end of spindle 17 is shaped to support a target (not shown) for indicating the position of the switch.

Pinned to the spindle 17 is a sleeve 20 having an ear 21 to which the operating arm 24 is pivoted. The sleeve 20 also has a lug 22 supporting a lock eye 23 through which a padlock (not shown) may be passed for locking the switch stand.

The operating arm or drop lever 24 is forked to straddle the sleeve 20 and has ears 25 embracing ear 21 through all of which pivot bolt 26 passes. Part of the arm 24 is shaped to form a housing 27 seating a spiral spring 28 engaging between the

55

bottom of the housing 27 and the lug 22 to urge the operating arm downwardly. The side of housing 27 is provided with a small eye 31 to which the chain of the padlock may be secured.

5 Formed preferably integral with the operating arm 24 are laterally extending plate members 32 having depending flanges 33. These plate members 32, depending flanges 33, together with the hinged ears 21 and 25 and housing 27 form a 10 protecting housing or covering for the four slots 30 in the star block 15, thus protecting these slots from the introduction of foreign matter no matter to what position the switch stand is thrown.

Pivoted by pivot bolt 36 to the side of casing 10 15 is hand lever 34. This hand lever is provided with a slot 35 in which the operating arm 24 engages.

To operate the switch stand, hand lever 34 is moved in a vertical plane from one position to 20 the other in the same manner as explained in the above mentioned Kidd patent. The first part of the movement of hand lever 34 raises operating arm or drop lever 24 out of its slot 30, after which further movement of the hand lever 34 moves operating arm 24 in a horizontal plane, causing it 25 to drop in the next notch 30, this dropping being assisted by the spring 28. The horizontal movement of arm 24 rotates the spindle 17 which operates the switch. The protective shroud formed by plates 32 and flanges 33 loosely telescopes the 30 circular top of star block 15 and partakes of both vertical and circular movement with drop lever 24.

When the switch stand is operated automatically by the passage of trains through the switch, 35 the star block 15, sleeve 20 and operating arm 24 carrying the protective housing or shroud for the slots rotate as a unit, without changing the relation of the slots to their protecting housing.

40 Thus, the present construction increases the safety and reliability of this type of switch stand. The new construction guards all of the slots against all foreign matter likely to lodge in the slots,—the padlock chain, dirt, ballast, snow and ice. It will be noted that, as the operating arm 45 24 is raised, the protective housing formed by plates 32 and depending flanges 33 rises and rotates with the arm, but at no time are any of the slots 30 exposed to the weather or in such position that any foreign matter, such as the chain on the padlock, can drop in and interfere

with the safe and quick operation of the switch stand. In the prior construction foreign matter was liable to collect in the slots in the star block and interfere with the hand operation of the stand. The provision of a protecting housing or 5 casing formed integral with the operating arm fully guards these slots and protects them from all foreign matter, insuring safe and speedy seating of the operating arm in the slot to which it is moved at all times. 10

While certain novel features of the invention have been disclosed and are pointed out in the annexed claim, it will be understood that various omissions, substitutions and changes may be made by those skilled in the art without depart- 15 ing from the spirit of the invention.

What is claimed is:

In a switch stand, a casing, a block journalled in said casing, spring devices in said casing for yieldably holding said block in any of four, pre- 20 determined rotary positions, a vertical shaft mounted in said block and casing and having means for connection to a switch, a sleeve secured to said vertical shaft and having a hinge ear, a drop lever comprising a forked portion straddling 25 said sleeve and projecting ears embracing said first-mentioned ear, a horizontal pivot member passing through said ears, said drop lever carrying a seat, said sleeve carrying an abutment, a spring between said seat and abutment, said drop lever 30 having a housing surrounding said spring, said block having a circular top provided with four slots into which said drop lever seat is adapted selectively to rest, a hand lever pivoted to said casing and having a cam slot through which said drop 35 lever extends, said drop lever carrying, on either side, horizontally extending plate portions extending out from said housing and forked portion close above the corresponding slots, said 40 plate portions having curved skirt portions concentric with said circular top and depending below the tops of the outer ends of said corresponding slots, said plate and skirt portions extending substantially from said projecting ears to the outer edge of said housing, said plate and skirt 45 portions forming a protecting shroud loosely telescoping over said circular top and protecting the slots on either side of any slot in which said seat rests, said shroud having both vertical and circular movement with said drop lever.

SAMUEL L. EASTBURN.
